SPINNING DEVICE

Cortland Hatfield, Elizabethton, Tenn., assignor,
by mesne assignments, to Beaunit Mills, Inc.,
New York, N. Y., a corporation of New York

Application June 4, 1946, Serial No. 674,237

2 Claims. (Cl. 18—8)

1

This invention relates to improvements in rayon manufacturing equipment and more particularly to the spinning heads and funnels commonly employed in the cuprammonium cellulose stretch spinning system, as disclosed, for example, in U. S. Patents Nos. 1,596,086, 1,828,497, etc.

The primary object of this invention is to simplify the construction and assembly of the spinning head and funnel while preserving the efficiency of the device.

Among its features the invention embodies a spinning head comprising a minimum number of parts which may be assembled without the use of cement, and a spinning funnel having a frustroconical ring or collar which cooperates with a tapered seat in said head to form a fluid tight joint.

Referring to the accompanying drawings wherein a preferred embodiment of my invention is shown:

Fig. 1 is a side view partly in section of a spinning head and funnel assembled in accordance with the present invention.

Fig. 2 is a bottom plan view of the dome or upper part of the spinning head.

Fig. 3 is a side view partly in section of the spinning liquid distributor.

Fig. 4 is a fragmentary side view of a spinning funnel made in accordance with this invention, and

Fig. 5 is a perspective view of the clamping ring used for holding the funnel in the head.

Referring to the drawings in detail, the spinning head proper comprises a dome designated generally 10 and a liquid distributor designated generally 11.

The dome 10 comprises a substantially cylindrical body 12 carrying at its upper end a projecting peripheral flange 13 and at its lower end a projecting peripheral flange 14. The flange 14 is provided at spaced intervals with internally screw-threaded bolt holes 15, the axes of which extend parallel to the axis of the body 12. Extending inwardly from the upper end of the body 12 is a dome-like portion 16 having a relatively large central opening 17 for the reception of a spinnerette mounting 18 carrying a spinnerette 19 through which spinning solution is introduced into the spinning head. Formed on the lower end of the body 12 is a depending collar 20 which serves to locate the parts during assembly, as will be more fully hereinafter described.

The liquid distributor 11 above referred to comprises a base plate 21 having an internally tapered bore forming a seat 22 and in its upper face an

2

annular groove 23. Formed at spaced intervals in the plate near its periphery are bolt holes 24 which, when the parts are assembled, align with the bolt holes 15 in the flange 14 of the dome 10. Extending upwardly from the grooved surface of the base plate 21 is a wall 25, the outer surface of which tapers toward its upper end, while the inner surface is cylindrical and aligns with the smaller diameter of the seat 22. Extending outwardly from the wall 25, at its junction with the base plate 21 and partially overhanging the groove 23, is an annular flange 26 which, when the parts are assembled, cooperates with the inner surface of the body 12 in forming a constricted annular passage, as shown in Fig. 1. Opening into the groove 23 from an angular direction is a base 27 which terminates at its opposite end in an internally screw-threaded base 28 for the reception of a coagulating liquid supply pipe 29, as depicted in Fig. 1.

In Fig. 4 there is illustrated a conventional spinning funnel 30 having formed near its upper end an outstanding annular flange 31, the outer peripheral surface of which tapers toward its upper end to the same degree as the seat 22 tapers. The largest diameter of the flange 31 is slightly greater than the largest diameter of the seat 22 so that, when the parts are assembled, flange 31 will not wholly enter the bore in the base plate 21. A clamping ring 32, as shown in Fig. 5, is provided at spaced intervals with bolt holes 33 which are adapted to align with the bolt holes 15 and 24 for reception of clamping bolts 34. The ring 32 is recessed at 35 to accommodate the liquid supply pipe 29 shown in Fig. 1.

As illustrated in Fig. 1, the parts are assembled by seating the lower face of the flange 14 of the dome 10 upon the upper face of the base plate 21 of the liquid distributor 11 with the collar 20 projecting into the groove 23, as shown. This serves to accurately locate the parts, and at the same time assures a fluid tight joint between the parts. It is of course understood that, in so assembling the parts, the bolt holes 15 and 24 are placed in alignment. Having thus fitted the dome 10 and liquid distributor 11 together, the larger end of the spinning funnel 30 is introduced from below into the tapered opening in the base plate 21 and up into the cylindrical part of the wall 25 until the conical flange 31 contacts the seat 22 in liquid tight engagement therewith. The clamping ring 32 is next slipped over the smaller end of the funnel 30 and so adjusted as to cause the recess 35 to receive supply pipe 29 and the bolt holes 33 to align with the bolt holes

34. Bolts 34 are then inserted in the bolt holes with their threaded ends engaging the internally threaded bolt holes 15 and turned up to draw the parts together in fluid tight contact. It will be seen in Fig. 1 that, when the parts are thus assembled, liquid entering through pipe 29 will flow around the groove and thence upwardly between the outer face of the flange 26 and the inner face of the body 12 with these parts cooperating to form a constricted annular passage through which the liquid flows upwardly and finally overflows the upper edge of the wall 25 and thence down along the inner surface of wall 25 into the annular space 36 formed by the portion of the funnel extending upwardly beyond the flange 31 and said inside wall 25 and thence into the spinning funnel 30. It is of course to be understood that liquid in sufficient volume is supplied through pipe 29 to keep the spinning funnel completely filled irrespective of the volume of liquid discharged from the lower end of the funnel 30.

It is of course to be understood that this device can be used in funnel spinning of any spinning solution, such as cuprammonium cellulose, viscose, casein, cellulose ethers, cellulose esters, etc.

It is furthermore to be understood that the foregoing detailed description and drawings are given merely by way of illustration and that many variations may be made therein without departing from the spirit and scope of my invention.

I claim:

1. In a spinning head and funnel assembly, a liquid distributing member comprising a base plate having a central opening which tapers upwardly, an annular wall rising from the base plate in alignment with the upper smaller end of the opening, said base plate having an annular groove in its upper face at the junction of the outer face of the wall and the base plate and having also a liquid inlet port communicating with the groove from below, a liquid-flow constricting flange on the annular wall partially overhanging the groove, a dome removably seated on the upper face of the base plate in spaced relation to the annular wall, a spinning funnel insertable through the tapered opening in the base plate said funnel having a relatively narrow frustro-conical flange disposed a short distance below its top edge and extending peripherally about and radially from said funnel and having a tapered peripheral surface corresponding to the taper of the opening in the base plate, an annular member bearing against the bottom surface of said flange and pressure exerting means cooperating with said dome, said base plate and said annular member to force said member

against the bottom surface of said flange and said flange into its seat in said tapered opening and to retain said dome, said base plate, said funnel, and said annular member in assembled relation.

2. In a spinning head and funnel assembly, a liquid distributing member comprising a base plate having a central opening which tapers upwardly, an annular wall rising from the base plate in alignment with the upper smaller end of the opening, said base plate having an annular groove in its upper face at the junction of the outer face of the wall and the base plate and also having a liquid inlet port communicating with the groove from below, a liquid-flow constricting flange on the annular wall partially overhanging the groove, a dome removably seated on the upper face of the base plate in spaced relation to the annular wall, a spinning funnel insertable through the tapered opening in the base plate said funnel having a relatively narrow frustro-conical flange disposed a short distance below its top edge and extending peripherally about and radially from said funnel and having a tapered peripheral surface corresponding to the taper of the opening in the base plate, an annular member bearing against the bottom surface of said flange, pressure exerting means cooperating with said dome, said base plate, and said annular member to force said member against the bottom surface of said flange and said flange into its seat and to retain said dome, said base plate, said funnel and said annular member in assembled relation, the outside surface of said funnel above said flange being spaced from the inside surface of said annular wall rising from said base plate to form an annular receiving channel for liquid overflowing the top of said annular wall in its passage to the interior of said funnel.
